WILLIAM KIDD, OF DUNCAN'S MILLS, CALIFORNIA.

Design No. 4,706, dated March 14, 1871.

DESIGN FOR SAWS.

The Schedule referred to in these Letters Patent and making part of the same.

To all whom it may concern:

Be it known that I, WILLIAM KIDD, of Duncan's Mills, in the county of Sonoma and State of California, have invented a new and original Design for Saws; and I do hereby declare that the following is a full, clear, and exact description thereof, which will enable others skilled in the art to make and use the same, reference being had to the accompanying drawing forming part of this specification.

The nature of my design is fully represented in the accompanying drawing, to which reference is made.

I claim as my invention—

The design for a saw, as shown.

The above specification of my invention signed by me this 2d day of February, 1871.

WILLIAM ^{his} X KIDD.
